UNITED STATES PATENT OFFICE

GEORGE A. METCALF, DECEASED, LATE OF FRAMINGHAM, MASSACHUSETTS, BY ELLA M. METCALF, ADMINISTRATRIX, OF FRAMINGHAM, MASSACHUSETTS, AND JAMES D. BRUCE, OF FRAMINGHAM, MASSACHUSETTS, ASSIGNORS TO DRAPER CORPORATION, OF HOPEDALE, MASSACHUSETTS, A CORPORATION OF MAINE

SLUB CATCHER AND YARN CLEANER

Application filed November 6, 1930. Serial No. 493,828.

This invention relates to slub catchers and yarn cleaners such as are employed in connection with spoolers and other textile machines for the cleaning off from yarn of slubs, irregularities, imperfections, and foreign matter or, in other words, for preventing the passage of the yarn unless it is in the condition required for further use.

The object of this invention is to provide such a slub catcher and yarn cleaner in which the yarn passage is a parallelogram, thus presenting four properly disposed scraping edges to the yarn as it passes therethrough.

The object of the invention is further to provide such a device in which the area of the parallelogram-shaped yarn passage may be varied as found desirable and in accordance with the size of the yarn being handled by adjusting either one side or two adjacent sides of the yarn passage.

The object of the invention is further to provide such a device in which one side wall of the yarn passage is movably, and preferably yieldingly movably, mounted so as to permit ready threading of the passage.

These and other objects and features of the invention will appear more fully from the accompanying description and drawings and will be particularly pointed out in the claims.

As the general nature and use of slub catchers and yarn cleaners are well known and familiar to those skilled in the art, it is only necessary here to illustrate and describe a preferred form of construction embodying the present invention and such a preferred form is shown in the drawings, in which:

Fig. 1 is a rear elevation of the device as supported on the traverse rod of a spooler.

Fig. 2 is a front elevation of the construction shown in Fig. 1.

Fig. 3 is a side elevation of the same construction.

Fig. 4 is an enlarged detail view in front elevation showing the parts surrounding the thread passage.

Fig. 5 is a view in cross section taken on the line 5—5 of Fig. 4.

Fig. 6 is a view in cross section taken on the line 6—6 of Fig. 4.

While the general cross sectional shape of yarn is circular, it varies substantially therefrom and is frequently more or less flattened. It is desirable, however, that the cross section of yarn should approximate the circular. It is difficult and practically impossible to form a thread passage in a slub catcher and yarn cleaner of circular form and at the same time provide for adjustment of the area of the passage. In this invention the cross-sectional area of the yarn passage is that of a parallelogram and preferably equilateral or square. Thus there is presented to the yarn, as it passes through the device, four scraping edges and as the yarn twists and turns in its passage through the device any slubs, imperfections, or other foreign matters are removed or, if these are too large, the yarn is broken. Such a construction acts to maintain the desired cross section of the yarn and maintain it substantially circular. Such a construction also is readily adjustable, in accordance with this invention, to vary to any required extent the area of the yarn passage preferably by adjusting two adjacent side walls of the passage, although the area may be varied to the required extent by the adjustment of one side wall. The invention also presents a simple and efficient provision for threading the yarn passage in that one side wall is movably mounted, and preferably yieldingly movably mounted, so that this side wall may be pushed aside by the yarn and the yarn allowed to enter the passage.

In the construction illustrated, there is shown the traverse rod 1 of a yarn handling machine such as a spooler. On this traverse rod is clamped an upstanding bracket 2 and a preferred embodiment of the slub catcher and yarn cleaner is conveniently carried on this bracket.

The device is shown as comprising a main body or support formed of a pair of plates 3 and 4 spaced apart by suitable separators 5 and 6 and positioned by pins such as 7 and a clamping bolt 8 which is also conveniently utilized for clamping the support to the bracket 2. The plates 3 and 4 are slotted

down from the top at 9 to present a threading passage.

The thread cleaning passage extends through the plates 3 and 4 and one side wall 5 is presented by the plates 3 and 4 of the support. This side wall is shown at 10 at the left-hand side. The opposite side wall 11 is shown as formed on a wall member or plate 12 mounted in the support for adjustment toward and from the side wall 10. For this purpose the plate 12 is guided by pins 13 and is locked in adjusted position by a set screw 14 extending through an enlarged aperture in the plate into the support. As 15 illustrated, the plate 12 fits on the outer surface of the plate 3 and is provided with an end carrying the side wall 11 projecting into a recess in the plate 3, but any suitable construction may be provided for this side 20 wall. The third side wall 15 of the yarn passage is shown as formed on a wall member or plate 16 mounted between the plates 3 and 4 and guided toward and from the axis of the passage against the spacer 6 and 25 by a slot therein fitting over a bolt 17. Thus the plate 16 may be moved in or out and held in locked position by the bolt 17 to provide the desired adjustment. The fourth side wall 18 of the yarn passage is formed on 30 a wall member or plate 19 extending between the plates 3 and 4 and pivotally secured thereto by the stud 20. This plate 19 is yieldingly pressed against a stud 21 mounted in the plates 3 and 4 by a spring 22 mounted 35 between these plates and held in position by a stud 23. Thus it will be seen that by pressing the yarn down in the slot 9, the plate 19 will swing aside and allow the yarn readily to be threaded into the yarn passage.

The cross sectional area of the yarn passage, it will be seen, is a parallelogram and is preferably equilateral, being readily adjusted to any required size by adjusting the 45 plates or wall members 12 and 16. While this yarn passage is shown as having a shape of a rhomb, that will depend upon the angular relation of the plate 16 and the opposed plate 19 and any desired angular relation 50 by which the yarn passage may be square or approximately square is readily obtained.

The plates 12, 16, and 19 are all readily removable and the side wall 10 of the yarn passage is preferably formed on wear plates 55 24 inserted in the plates 3 and 4 so that all four walls of the yarn passage may be made of special or specially hardened metal and removed and replaced when wear takes place.

The area of the yarn passage may be adjusted to maintain its equilateral form by 60 adjusting both plates 12 and 16 or may be adjusted to give an elongated area by adjusting either one of these plates. In all cases, however, there is presented to the 65 yarn 4 oppositely disposed scraping edges

which act efficiently to clean the yarn and present a passage, the area of which may be adjusted as and to the extent desired.

Having thus described the invention, what is claimed as new, and desired to be secured 70 by Letters Patent is:

1. A slub catcher and yarn cleaner having a yarn passage whose cross section is a parallelogram with one side wall of said passage movable without disturbing the other three 75 side walls to open and close the passage and thus permit threading.

2. A slub catcher and yarn cleaner having a yarn passage whose cross section is a parallelogram with one side wall on a member 80 yieldingly movable without disturbing the other three side walls to open and close the passage and thus permit threading.

3. A slub catcher and yarn cleaner having a yarn passage whose cross section is a parallelogram and separate means for adjusting each of two adjacent side walls to vary 85 the size of the passage.

4. A slub catcher and yarn cleaner having a yarn passage whose cross section is a parallelogram, means for adjusting one side wall without disturbing the other three side walls to vary the area of the passage and with a single one of the said other three side walls yieldingly movable to open and close 95 the passage and thus permit threading.

5. A slub catcher and yarn cleaner having a yarn passage whose cross section is a parallelogram and separate means for adjusting each of two adjacent side walls to vary the 100 size of the passage and with a single third side wall yieldingly movable to open and close the passage and thus permit threading.

6. A slub catcher and yarn cleaner having a yarn passage whose cross section is a parallelogram and comprising a support presenting one side wall of said passage, a wall member presenting the opposite side wall of said passage adjustable on the support toward and from the first side wall, a wall 110 member presenting the third side wall of said passage adjustable on said support toward and from the axis of the passage, and a wall member presenting the fourth side wall of the passage and movably mounted 115 on the support to permit threading of the passage.

7. A slub catcher and yarn cleaner comprising the construction defined in claim 6, in which the fourth side wall member is pivotally mounted on the support and yieldingly held in position and permitting threading of the passage when swung on its pivot.

In testimony whereof, we have signed our names to this specification.
